UNITED STATES PATENT OFFICE.

FRANK BABCOCK, OF FARWELL, MICHIGAN.

PUMP STOP.

1,410,282.

Specification of Letters Patent. Patented Mar. 21, 1922.

Application filed April 17, 1918. Serial No. 229,150.

To all whom it may concern:

Be it known that I, FRANK BABCOCK, a citizen of the United States, residing at Farwell, in the county of Clare and State 5 of Michigan, have invented certain new and useful Improvements in a Pump Stop, of which the following is a specification.

This invention relates to automatic switch trips and more particularly to a device for 10 automatically stopping a motor driven pump when the pressure produced by the pump has reached a certain predetermined point.

One of the objects of the invention is to 15 provide a mechanism associated with a pressure regulator valve of the type commonly employed in water pumping systems whereby the mechanism will be actuated when part of the valve structure is actuated during the course of operation of the pump.

20 A further object of the invention is to provide a weight operated switch trip associated with the valve stem of a pressure regulator valve whereby the weight may be actuated when the valve stem is moved in 25 one direction for causing the weight to be released to automatically actuate or open an electric switch in the circuit of the driving motor.

30 A further object of this invention is to provide a device of this character which consists of comparatively few parts and is simple in construction, but durable and well adapted to withstand the rough usage to 35 which devices of this character are ordinarily subjected.

For a full description of the invention and the advantages and merits thereof, reference is to be had to the following description and accompanying drawings, in 40 which:

Figure 1 is an elevation of a motor driven water pump showing the invention applied thereto.

Figure 2 is a section taken on the line 45 2-2 of Fig. 1, and looking in the direction indicated by the arrow.

Figure 3 is a detail perspective view of a portion of the invention.

Referring to the drawings, wherein is 50 illustrated the preferred form of my invention, in which like numerals of reference indicate corresponding parts throughout the several views, the pump A, which may be of any preferred type is driven by the electric motor B which in this instance, is provided with a driving belt C passing over

suitable pulleys to drive the pump when the motor is in operation. In this connection, it is to be understood that the drive between the pump and motor may be of any 60 other type, that is by gearing or chains and sprockets. In motor pumping systems of this character, a pressure regulator valve D is provided and, in the illustrated type, the valve is provided with a vertically reciprocal valve stem E which is actuated by the varying pressure caused by the operation of the pump.

An upright standard 1 is mounted upon a base 2 and has its upper end recessed to 70 receive a portion of the pipe F from the pressure regulator valve thereby rigidly holding the standard 1 which supports a pivoted arm 3 having a pivot bolt 4 adapted to be received in any of the openings 5 provided 75 in the standard 1 as shown to advantage in Fig. 2 of the drawing. A sliding weight 6 is mounted upon the arm 3 and is provided with a set screw to hold the weight at the desired point on the arm. The end of the 80 arm 3 beyond the weight 6, is connected to a flexible cable 7 which passes over a pulley 8 supported by a bracket 9 which may be held in elevated position in any preferred manner. In the present instance, this 85 bracket is connected to conveniently disposed pipes which are included in the system. Hangers 10 depend from the ceiling and support the cable 7 whereby it may be extended toward the side wall of the building 90 in which the system is installed. The wall of the building is provided with a knife-switch 11, the handle of which is fastened to the end of the cable which also passes over suitably arranged pulleys 12 and 13 adapted 95 to cause the cable to exert an outward pull on the handle of the switch 11 when the weighted end of the arm 3 is dropped.

Pivotaly mounted on the base 2 is a hook 14 having a bill 15 adapted to engage the 100 free end of the pivoted arm 3 to hold this arm downwardly against the action of the weight 6. This hook is connected to a flexible cable or pull wire 16, the opposite end of which is joined to a connecting arm 17 105 as shown in detail in Fig. 3 of the drawing. This arm 17 is attached to a portion of the mechanism of the pressure regulator valve D and has one end recessed as indicated at 18 to fit around the valve stem E and is 110 fixed to the cross-head G by extending one of the rods H through a convenient open-

ing 19 in the arm and threading the nut J on the rod and in binding contact with the arm 17 as shown in Fig. 3 of the drawing. It will be obvious, therefore, that this arm 17 will act to pull the pull wire 16 to disengage the hook 14 from the end of the arm C when the valve stem E is moved upwardly. The pull wire 16 passes over a pulley 20 mounted in a bracket carried by a support 21 which is disposed vertically and has its upper end secured to a portion of the piping as shown to advantage in Fig. 1. The fastening of the support is accomplished by a yoke 22 which includes complementary members embracing the pipe and bolted together to permit mounting and demounting as desired.

The driving motor B is connected to the conductors 23 and 24 which lead to the switch as more clearly shown in Fig. 2. The contacts of the switch 11 are connected with means which leads from the source of current.

When the parts are assembled as above described, the weight W on the pressure regulator valve will be set to cause an actuation of the valve stem E when a predetermined pressure has been reached. The movement of the valve stem will cause a pull to be exerted on the pull wire 16 which will cause the hook 14 to disengage the end of the arm 3, whereupon the weight 6 will cause the opposite end of the arm to drop thus exerting a pull on the cable 7, which will throw the switch to open position, thereby stopping the motor and consequently the pump.

The foregoing description and the drawings have reference to what may be considered the preferred or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. A switch trip comprising a switch, a regulator having a plunger stem, a pivoted arm having one end provided with a weight, a hook releasably engageable with the opposite end of the arm to maintain the weighted end in raised position, a flexible element connecting the said hook with said plunger stem, and a cable attached to the said weighted end of the arm and to the switch and adapted to be pulled when said hook is

released for dropping the weighted end of the arm. 60

2. A switch trip comprising a switch, a regulator including a movable plunger stem having a cross head attached thereto, a connecting arm fixed to the cross head and movable therewith when the plunger stem is actuated, a weighted arm having a pivot provided intermediate its ends, the weight being disposed at one end of the arm, means for releasably holding the opposite end of the arm, a flexible cable connected to said means and said connecting arm, and means for connecting the weighted end of the arm to the said switch. 65

3. A switch trip comprising a switch, a regulator having a movable plunger stem, a standard, an arm pivotally mounted upon said standard and having one end provided with a weight, a hook releasably engageable with the opposite end of the arm to maintain said weighted end in raised position, a flexible element connecting the said hook with said stem, and a cable attached to the weighted end of the arm and to the switch and adapted to be pulled when said hook is released for dropping the weighted end of the arm. 70

4. A switch trip comprising a trip, a regulator having a movable plunger stem, a standard having a plurality of apertures therein, an arm, a pin for mounting said arm in said apertures, a hook releasably engageable with the opposite end of the arm to maintain the weighted end in raised position, a flexible element connecting the hook with the stem, and a cable attached to the weighted end of the arm and to the switch and adapted to be pulled when the hook is released for dropping the weighted end of the arm. 75

5. In combination, a support, a lever pivoted on the support, and provided with a weight adjacent one end, a cable attached thereto, a switch in engagement with the upper end of the cable and adapted to be opened when the weighted end of the lever moves downwardly, means for normally holding the lever in a raised position, a second cable attached to said means, and means for pulling the second cable so as to release the holding means. 80

In testimony whereof I affix my signature in presence of two witnesses.

FRANK BABCOCK.
